DESIGN.

J. NEIL.

CARPET.

No. 17,781.

Patented Oct. 11, 1887.

UNITED STATES PATENT OFFICE.

JOHN NEIL, OF BROOKLYN, NEW YORK, ASSIGNOR TO THE BIGELOW CARPET COMPANY, OF CLINTON, MASSACHUSETTS.

DESIGN FOR A CARPET.

SPECIFICATION forming part of Design No. 17,781, dated October 11, 1887.

Application filed August 30, 1887. Serial No. 248,311. Term of patent 3½ years.

To all whom it may concern:

Be it known that I, JOHN NEIL, of Brooklyn, in the county of Kings and State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design is adapted for the border of a stair-carpet. It has an inner ornamental edge. The middle portion is ornamented with large conventional flower forms having a circular

or nearly circular center, around one side of which project straight radial leaves and from the other side of which hangs a cluster of leaves. These figures occur at intervals, and are connected partly by a broad conventionalized stem-work and partly by a more slender stem. This stem work supports small circular flowers and leaves, with a few other forms between the large flower forms. My border has an outer margin of geometrical ornamentation.

What I claim as new, and desire to secure by Letters Patent, is—

The design for a carpet border, consisting of the design substantially as shown.

JOHN NEIL.
